SILK-TWISTING MILL AND LIKE MACHINE

Application filed April 25, 1929, Serial No. 358,100, and in France May 7, 1928.

This invention relates to silk-twisting mills and similar machines comprising twisting spindles which rotate to twist a textile thread or yarn, and reels on which the twisted product is wound.

In such machines, the twist is a function of the ratio between the angular speed of the spindle and the linear speed of the thread on its way to the collecting reel.

10 The known machines generally comprise an endless belt contacting with a number of spindles to frictionally drive the same, and friction wheels driving the collecting reels, these wheels being keyed on a common shaft 15 which is mechanically connected with the belt-driving gear. With such an arrangement the linear speed of the thread is substantially constant, but the angular speed of the spindles varies owing to the unavoidable 20 slips. The wear also reduces the diameter of the spindles, so that a worn spindle tends to rotate at a higher speed than a new one. On the other hand, even with a perfect machine, the twist is the same for all the threads and 25 it is impossible to manufacture, on the same mill, threads of different twist.

According to this invention, each reel is separately driven by the corresponding spindle through an appropriate gearing comprising 30 change-speed means which permit to adjust the twist.

The annexed drawing diagrammatically shows one element of a twisting mill according to the invention.

35 The spindle 1 supporting the bobbin 2 is driven by an endless belt 3 in the well-known manner. The thread 4 is wound on a reel 5 which is driven by a friction wheel 6. As shown, wheel 6 acts on the cylinder formed 40 by the thread already wound on reel 5, with the result that the linear speed of thread 4 is equal to the peripheral speed of wheel 6.

Spindle 1 is provided with a worm 7 meshing with a worm-wheel 8 keyed with a pinion 45 9 which in turn meshes with a gear wheel 10, loose on its shaft 15. Wheel 10 is keyed with a pulley 11 which, through a belt or string 12, drives a pulley 13 keyed with friction wheel 6. An idler 14 is provided to tension 50 the belt or string 12.

The shaft 15 of gear wheel 10 may be adjusted in position in an elongated opening 16 provided in an arm 17 integral with the gear case 18 in which the worm gear is enclosed. This arrangement permits to adjust the twist 55 by changing wheel 10 or pinion 9. This adjustment could also be performed by providing stepped pulleys in lieu of pulleys 11 and 13.

The thread guide 19 is preferably controlled in the usual way, all the thread guides of the mill being driven by the same mechanism. But it could also be controlled by a separate gear driven from wheel 6.

It will be easily understood that with the arrangement described, the twist is quite independent of the slip of belt 3 on spindle 1 and also of the diameter of the latter. Moreover, the twist of an element can be adjusted irrespective of the other elements of the mill. 70

We claim:

A silk twisting mill comprising a spindle to support a bobbin of untwisted yarn, a reel on which the yarn in the twisted state is wound, means for driving said reel from said spindle comprising a friction wheel contacting on the cylinder formed by the yarn already wound on the reel, a pulley fixedly carried by said friction wheel, a worm screw carried by said spindle, a worm wheel meshing with said worm screw, a pinion fixed to said worm wheel, a shaft, a gear wheel loose on said shaft meshing with said pinion, a pulley fixedly carried by said gear wheel and a tensioned belt passing round said two pulleys. 85

In testimony thereof we affix our signatures.

LOUIS CASIMIR JUNILLON.
